UNITED STATES PATENT OFFICE.

JAMES H. MACLAUGHLAN, OF NEW YORK, N. Y.

LOCOMOTIVE-DRAFTER.

1,160,305.

Specification of Letters Patent. Patented Nov. 16, 1915.

Application filed April 1, 1915. Serial No. 18,488.

To all whom it may concern:

Be it known that I, JAMES H. MACLAUGHLAN, a citizen of the United States of America, residing at New York city, in the county and State of New York, have invented certain new and useful Improvements in Locomotive-Drafters, of which the following is a specification.

My invention relates to an improved locomotive drafter.

Devices of this kind usually form part of a roundhouse equipment, and serve to induce draft in a locomotive furnace to restore the locomotive to service condition after its fires have been banked, or drawn, for various reasons.

Locomotive drafters include, as essential elements, a fan or exhauster and an uptake pipe for connecting the stack of a locomotive with the fan. To secure the greatest efficiency in operation of the drafter it is necessary that the action of the fan on the locomotive furnace shall be as vigorous as possible, and the primary purpose of my invention is to provide a construction wherein the maximum efficiency of the fan is obtainable. I accomplish this object by so arranging the fan that it may revolve in a horizontal plane, and by connecting the locomotive stack to the fan by means of a straight uptake pipe, free of all bends or elbows likely to detract from the effective suction action of the fan. The uptake pipe is preferably of telescopic construction, so as to be capable of increase or decrease in length to connect with engine stacks of varying height, and this pipe should also be adapted to move from side to side, or swung in a vertical plane, so as to be moved over and away from the outlet of the engine stack. It has heretofore been usual to provide separate controlling means for increasing or decreasing the length of the uptake pipe, and for swinging the same from side to side. This arrangement is cumbersome, and time consuming in operation, and another object of my invention is to provide means, operable from a single controlling point, for increasing or decreasing the length of the uptake pipe as well as for moving it from side to side. Such controlling means preferably include a flexible cord or chain depending to a point near the roundhouse floor within convenient reach of an operator.

The detail construction and operation of the invention will be clearly understood from the following description thereof, in connection with the accompanying drawing, wherein—

Figure 1 is an end elevational view of the improved locomotive drafter, showing the uptake pipe in position over the locomotive stack outlet, the dotted line position illustrating the oscillating or swinging capacity of this pipe; Fig. 2 is a side elevational view thereof; and Fig. 3 is a detail view, partly in section, of a part of the means for operating the uptake pipe.

Referring to the drawing, 10 denotes the roof of a round house, upon which is supported a head house 11, inclosing the suction mechanism for the locomotive drafter.

Resting upon the round house roof 10, are the supporting arms 12 for a fan or exhauster 13. This fan may be of any approved type, but it is essential for the purpose of my invention that it be arranged to revolve in a horizontal, or substantially horizontal plane, as indicated in the drawing. The fan is preferably driven by an electric motor, designated as a whole by the numeral 14. The operation of the motor is switch controlled as usual.

The casing of the fan 13 is suitably connected with an offtake pipe 15, which projects beyond the head house roof, and serves to conduct the exhaust products of the fan 13 to atmosphere at a point higher than the top of the roundhouse.

Depending from the casing of the fan 13 is a nipple or relatively short pipe extension 16, in which is pivotally supported the upper end of the uptake pipe, consisting of the telescoping sections 17 and 18, the section 17 preferably, although not necessarily, telescoping within the section 18.

The edge of the nipple 16 is provided with, or formed as, a packed or gasketed flange 19 to prevent escape of steam or smoke between the uptake pipe and the nipple 16.

The upper end of the pipe 17—18 is preferably enlarged and substantially cylindrical as indicated at 17^a, and is pivotally supported by pins 20 carried in the hangers 21, secured to the casing of fan 13. Two pins 20 and two hangers 21 are used, although but one of each appears in the drawing. The lower end of the pipe 17—18 is pro-

vided with an enlarged cylindrical hood 22, designed to rest upon the outlet end of the stack 23 of a locomotive 24. Owing to the cylindrical inner configuration of the hood, a tight connection between the same and the stack 23 is obtained, even though the pipe 17-18 be inclined with respect to the stack, as shown in Fig. 1.

The side to side movement of the pipe is effected by the following instrumentalities:—Embracing the pipe section 17 below its enlarged head 17^a is a collar 25 projecting outwardly from the uptake pipe and secured in one leg of a substantially triangular socket 26. Secured in the other leg of the socket is one end of an inclined rod 27, the opposite end of which is secured to the pipe section 17 at about its median point. Projecting upwardly, from, and rigidly attached to, the apex of the socket 26 is a link 28 pivotally connected to an arm or lever 29 (Fig. 3) formed at one end of a sleeve or hollow shaft 30 which extends along the round house roof in a direction at right angles to the axis of pipe 17-18 when the latter is vertically pendent. The end of the sleeve 30 opposite that which carries the lever 29 is provided with a worm wheel 31 which meshes with a worm 32 on a short shaft 33 extending at right angles to shaft 30. The shaft 30 and the shaft 33 are supported in a bracket 34 fixed to the round house roof. At one end, the shaft 33 carries a grooved pulley 35 over which the endless operating cord 36 is rove. This operating cord extends down to near the round house floor within easy reach of a person standing on the floor.

Lengthwise adjustment of the uptake pipe 17-18 is secured by means of the following instrumentalities:—Attached to the pipe section 18, near its upper edge, is one end of a cable or wire 36 which passes over a sheave 37 on the side of pipe section 17, over a second sheave 38 in the socket 26, and has its opposite end secured to the periphery of a grooved pulley 39 (Fig. 3). Interposed between the sheave 38 and the pulley 39 is a guide 41 carried by and projecting out from the motor 14, and serving to support one end of shaft 40 and to guide the cord 36. The pulley 39 is carried near one end of a shaft 40 which is coaxial with, and surrounded by the sleeve 30. The end of the shaft 40 opposite that carrying the pulley 39 projects beyond the sleeve 30 and has secured thereto a worm wheel 42 meshing with a worm 43 formed on a shaft 44 which extends at right angles to the shaft 40. The shaft 44 is suitably supported on the round house roof, and carries at one end thereof a pulley 45 over which an endless operating cord 46 passes. The cord 46 extends down toward the houndhouse floor about the same distance as the cord 36.

The operation of the invention will be understood from the following description thereof. When an engine 24 is to be subjected to the action of the drafter, the cord 46 is pulled so that shaft 40 will be revolved in a direction to raise the section 18 of the uptake pipe a distance above the top of the stack 23 of the engine 24. Then one of the strands of cord 36 is pulled so as to rotate sleeve 30 in the proper direction to swing the uptake pipe into a position where the hood 22 will be over the outlet end of stack 23. Thereafter the proper strand of cord 46 is operated to lower the hood onto the stack 23 and the exhauster is put into operation. After completion of the exhausting action the section 18 is raised to clear the stack 23 and the locomotive 24 moves away. The pipe 17-18 may be permitted to remain in its last position until again required for use.

It will be noted that the lengthwise and side to side adjustment of the uptake pipe is controlled from one point by means of the cords 36 and 46, so that but one operator is required for the device. Furthermore, owing to the fact that the pipe 17-18 is straight from end to end, and the fan revolute in a horizontal plane, the full efficiency of the fan is availed of, and the placing of the locomotive into service condition is effected in the minimum space of time, thus effecting a substantial economy in power.

What I claim as new and desire to secure by Letters Patent is:—

1. A locomotive drafter, comprising an uptake pipe having one end adapted for connection with a locomotive stack, and exhaust means revolute in a substantially horizontal plane and communicating with the other end of said uptake pipe.

2. A locomotive drafter, comprising a straight uptake pipe having one end adapted for connection with a locomotive stack, and exhaust means revolute in a substantially horizontal plane and communicating with the other end of said uptake pipe.

3. A locomotive drafter, comprising a telescopic uptake pipe having one end adapted for connection with a locomotive stack, and exhaust means revolute in a substantially horizontal plane and communicating with the other end of said uptake pipe.

4. A locomotive drafter, comprising a telescopic uptake pipe having one end adapted for connection with a locomotive stack, exhaust means revolute in a substantially horizontal plane and communicating with the other end of said uptake pipe, and means for varying the length of said pipe.

5. A locomotive drafter, comprising a telescopic uptake pipe having one end adapted for connection with a locomotive stack, exhaust means revolute in a substantially hor-

izontal plane and communicating with the other end of said uptake pipe, and means for swinging said pipe from side to side.

6. A locomotive drafter, comprising a telescopic uptake pipe, having one end adapted for connection with a locomotive stack, exhaust means revoluble in a substantially horizontal plane and communicating with the other end of said uptake pipe, means for varying the length of said pipe, and means for swinging said pipe from side to side.

7. A locomotive drafter, comprising a telescopic uptake pipe, having one end adapted for connection with a locomotive stack, ex-

haust means revoluble in a substantially horizontal plane and communicating with the other end of said uptake pipe, means for varying the length of said pipe, and means for swinging said pipe from side to side, both said last named means including flexible operating members terminating at substantially the same point.

In testimony whereof I have affixed my signature in presence of two witnesses.

JAMES H. MACLAUCHLAN.
